METHOD AND APPARATUS FOR PRODUCING
WOODEN WALL COVERINGSOtto Reimann, Berlin-Charlottenburg,
Germany

Application June 2, 1931, Serial No. 541,728

8 Claims. (Cl. 144—279)

In the known methods of and apparatus for producing wooden wall coverings or veneers the device supplying the adhesive is arranged in the immediate vicinity of the point where the veneer and the backing are united, and at an invariable distance therefrom, so that the two sheets are caused to unite before the adhesive has acquired the desired tacky condition sufficient for proper connection. Upon the subsequent passage through a set of rolls or when taken over a drying cylinder folds are frequently caused as a result of displacement of the covering in relation to the backing, thus adversely affecting the quality of the product derived.

The subject matter of this invention is a method of producing wooden wall coverings or facings, in which the backing, after the application of the adhesive, is guided freely for a certain distance conforming with the nature of the adhesive employed, then united under pressure with the veneer taken from a roller, and after the connection the two webs or sheets are warmed, dried and if necessary cooled, to then, after acquiring the moist condition necessary for further operations (10-20%), be passed through a set of rollers and wound under tension in roll form. The adhesive may be applied to the backing either in the form of glue foil or in a liquid state. The drying of the wooden wall covering is preferably performed by means of a drying cylinder, which is adjustable as regards its spacing from the point where the two webs are united, whereby a snug adaptation of the wooden covering to the drying cylinder is ensured by an endless, pervious cloth, screen or band exerting a counter-pressure.

An apparatus for carrying out the method according to the invention is illustrated, by way of example, in the accompanying drawings.

Fig. 1 is a view showing the apparatus in elevation.

Fig. 2 is a plan view of the same apparatus.

Fig. 3 is an end view and Fig. 4 is a front view showing the drying device and the metal cloth for pressing the wooden wall covering against the drying cylinder.

Fig. 5 is a plan view of a wooden wall covering showing the superimposed elements thereof.

In the arrangement shown the backing, for example paper, is wound on a roller 1, which is mounted in the frame 2 of a gluing device. The latter consists of a container 3, which is borne by the frame, and the bottom of which is constituted by two rollers 4, 5, the spacing between these rollers being adjustable as desired by means

of a micrometer screw or the like for regulating the size of the gap.

After leaving the gluing device the web of paper is then conducted around a part of the periphery of the roller 5 and over a roller 6, to be thereupon united with the veneer. The frame of the adhesive-applying apparatus rests with rollers 7 on rails 8 and is made to be movable in a well known way as by means of a screw threaded rod 18 rotatably mounted in supports 19, 20 and 10 rotatable by a hand wheel 21, so that the distance of the adhesive-applying device from the pair of rollers 9, 10 uniting the web of paper with the veneer may be adjusted as desired. For instance, to effect adjustment of the adhesive applying device relative to the support 20 the thread on the rod 18 may engage the teeth of a gear or worm wheel 22 rotatably carried by the frame 2 and a second gear fixed to and rotatable with the worm wheel meshing with and rotating toothed wheels or pinions fixed on the axles or shafts of the rollers 7. The roller 10 is furnished with a rubber facing and presses against the roller 9. A preferably bulged roller 11 ensures a proper spreading and an even tension of the web of paper or fabric coated with the adhesive.

The moist veneer is wound upon a preferably braked roller 12 mounted in the frame, and is withdrawn from the roller under tension by the 30 rollers 9 and 10 and united under pressure with the web of paper. The whole, after its exit from the rollers 9 and 10, is thereupon conducted practically tangentially to a movable drying cylinder 14, which is supported by means of two 35 pairs of rollers rotatably mounted upon a carriage adjustable relative to the frame 20 carrying the uniting rollers 9, 10 and adapted to be retained in adjusted position by wedge blocks or the like, as shown in Figure 1. The wood veneer 40 preferably covers the whole surface of the drying cylinder as indicated in dash and dot line in Figure 1. When employing a liquid adhesive the requisite pressure for pressing the wooden covering and paper web against the drying cylinder 45 is obtained by reason of the pull exerted by a set of rolls 16.

By corresponding heating of the movable drying cylinder as by varying the number of the heating elements 24 it is possible to vary the percentage of moisture of the wood covering as desired. The adjustability of the distance between the adhesive-applying device and the point where the web of paper is united with the veneer also permits a free guiding of the web of paper coated 55

with adhesive over a distance varying in length dependent on the nature of the adhesive, whereby if necessary a blower 23 or other drying means may be situated above the web of paper for the purpose of more rapidly attaining the desired tacky condition of the adhesive that must be tacky enough for preventing the moist veneer from being displaced upon the backing, when being united with the latter. Since neither the moisture of the adhesive, nor the moisture of the veneer is always uniform, the regulation of the tacky condition of the adhesive provided on the backing is very important for the production of a good, smooth wooden wall covering. The adjustment of the drying cylinder in its distance from the point of connection of the two sheets prevents excessive sag and possibly also tearing of the united layers, the thickness and weight of which may considerably vary.

After emerging from the drying device heated by gas, steam, hot air or electricity the wooden covering, which in the meantime has been dried to about 10-20% of its original moisture necessary for the additional operations, is conducted under tension through a set of rolls 16, the lowermost roll of which is driven in the usual manner by means of a belt and a pulley mounted on the shaft of the said roll and exerts on the web the pull necessary for the passage thereof through the different devices. In the set of rolls the wall covering is furnished with a satin finish, by means of the smooth peripheral surfaces of the rolls pressed by their own weight against both surfaces of the wooden wall covering that is then wound on a roller 17.

In the construction as shown by the drawings the drying cylinder turns on four rolls, two of which are mounted at each side of a frame containing the means for heating the drying cylinder such as by way of electric resistances 24 or the like. The drying cylinder however may be mounted on an axle arranged in the frame.

As an alternative to applying the adhesive in moist condition it is also possible to apply the same to the paper, cardboard or other backing in the form of glue foil, which, for instance, may be heated by any well known means and unites the backing with the moist veneer and to then pass the whole length of wall covering through the drying device and the set of rolls. To ensure the web being securely united with the veneer an endless metal cloth or screen 25, such as used in paper making machines, is guided around the drying cylinder 14 in any well known or conventional way, as by means of a tangentially movable tensioning roll 28 and guide rolls 26 and 27 rotatably mounted in the frame of the driving cylinder 14. The heating of the drying device may be varied as desired dependent on the degree of moisture of the veneer. For reliable operation of the apparatus it is essential that the wall covering, for such time as the veneer and the backing have not become properly united, is not subjected to bends in different directions.

The finished product, as shown in Fig. 5, consists of the backing 29 and the veneer 31, which elements are united by a thin layer of adhesive 30. As the adhesive is sufficiently tacky to properly connect the two elements, the veneer and the backing, before uniting the same upon the drying cylinder the elements will not be displaced relative to each other and no folds or creases are produced with the result that a perfectly smooth product is obtained.

75 I claim:

1. A method for producing wooden wall coverings and veneers consisting in supplying adhesive in an adjustable degree to a backing, regulating the tacky condition of the coating by varying the distance of the coating device from the point, where the backing is united with a veneer taken from a roll, guiding the united veneer and backing in contact with a substantial portion of the surface of a drying cylinder of a large diameter and pressing the united web smoothly against the cylinder, and then rewinding it in roll form by exerting on the united end of the web a pull sufficient to unroll the webs from their supporting rolls.

2. A method for producing wooden wall coverings and veneers consisting in supplying adhesive in an adjustable degree to a backing, regulating the tacky condition of the coating by varying the distance of the coating device from the point, where the backing is united with a veneer taken from a roll and by warming the coated backing, guiding the united veneer and backing in contact with a substantial portion of the surface of a drying cylinder of large diameter loosely and rotatably mounted in a frame and pressing the united web smoothly against the cylinder, and then rewinding it in roll form by exerting on the united end of the web a pull sufficient to unroll the webs from their supporting rolls.

3. An apparatus for producing wooden wall coverings and veneers, comprising a device for supplying adhesive coating to a backing taken from a roll, means for varying and fixing the position of said coating device with respect to means for uniting the backing with a veneer taken also from a roll, a drying cylinder of large diameter loosely and rotatably mounted in a movable and fixable frame, means for guiding the united material in contact with a substantial portion of the surface of the cylinder and to a set of rolls arranged to furnish the united and warmed web with a satin finish by the pressure of the smooth peripheral surfaces of the said rolls and exert on the web a sufficient pull to ensure its passage through the aforesaid devices and over the heated surface of the drying cylinder, and means for rewinding the finished web in roll form.

4. An apparatus for producing wooden wall coverings and veneers, comprising a device for supplying adhesive coating to a backing taken from a roll, means for varying and fixing the position of said coating device with respect to means for uniting the backing with a veneer taken also from a roll, a drying cylinder of large diameter loosely and rotatably mounted in a movable and fixable frame, means for guiding the united material so as to keep the veneer side thereof in contact with the drying cylinder, a set of rolls arranged to furnish the united and warmed web with a satin finish by the pressure of the smooth peripheral surfaces of the said rolls and exert on the web a sufficient pull to ensure its passage through the aforesaid devices, and over the heated surface of the drying cylinder, and means for rewinding the finished web in roll form.

5. An apparatus for producing wooden wall coverings and veneers, comprising a device for supplying adhesive coating to a backing taken from a roll, means for varying and fixing the position of said coating device with respect to means for uniting the backing with a veneer taken also from a roll, a drying cylinder of large diameter loosely and rotatably mounted in a movable and fixable frame, means for guiding the united mate-

rial so as to keep the veneer side thereof in contact with the drying cylinder, means for causing the veneer side of the united web to be pressed against the heated surface of the cylinder through a great arc, a set of rolls arranged to furnish the united and warmed web with a satin finish by the pressure of the smooth peripheral surfaces of the said rolls and exert on the web a sufficient pull to ensure its passage through the aforesaid devices and over the heated surface of the drying cylinder, and means for rewinding the finished web in roll form.

6. An apparatus for producing wooden wall coverings and veneers, comprising a device for applying adhesive coating to a backing taken from a roll, means for varying and fixing the position of said coating device with respect to means for uniting the backing with a veneer taken also from a roll, a drying cylinder of large diameter loosely and rotatably mounted in a movable frame, means for heating the cylinder to an adjustable degree, means for keeping the veneer side of the united web against the heated surface of the cylinder through a great arc, a set of rolls arranged to furnish the united and warmed web with a satin finish and to exert on the web the necessary pull to ensure its passage through the aforesaid devices and over the heated surface of the drying cylinder, and means for rewinding the finished web in roll form.

7. An apparatus for producing wooden wall coverings, and veneers, comprising a support mounted to roll on rails, a roll of veneer backing on the support, a device on the support for applying adhesive coating to the backing, a rigid frame carrying a pair of rollers, a roll of veneer

in the frame arranged to be united with the backing by said latter rollers, a drying cylinder of large diameter loosely and rotatably mounted in a movable frame, means for heating the cylinder to an adjustable degree, means for keeping the veneer side of the united web against the heated surface of the cylinder through a great arc, a set of rolls for furnishing the united and warmed web with a satin finish and for exerting on the web the necessary pull to ensure its passage through the aforesaid devices and over the heated surface of the drying cylinder, and means for rewinding the finished web in roll form.

8. An apparatus for producing wooden wall coverings and veneers comprising a support mounted to roll on rails, a roll of veneer backing on the support, adhesive container on the support having at its bottom two rollers forming a gap of adjustable size arranged to apply adhesive to the backing, a rigid frame carrying a pair of rollers, a roll of veneer in the frame arranged to be united with the backing by said latter rollers, a drying cylinder of large diameter loosely and rotatably mounted in a movable frame, means for heating the cylinder to an adjustable degree, means for keeping the veneer side of the united web against the heated surface of the cylinder through a great arc, a set of rolls for furnishing the united and warmed web with a satin finish and for exerting on the web the necessary pull to ensure its passage through the aforesaid devices and over the heated surface of the drying cylinder, and means for rewinding the finished web in roll form.
